his Atty.

UNITED STATES PATENT OFFICE.

JOSEPH BORLAND, OF MARS P. O., PENNSYLVANIA.

SHOE-CALK SHARPENER.

SPECIFICATION forming part of Letters Patent No. 228,975, dated June 22, 1880.

Application filed February 3, 1880.

To all whom it may concern:

Be it known that I, JOSEPH BORLAND, of Mars P. O., in the county of Butler and State of Pennsylvania, have invented an Improved 5 Device for Sharpening the Calks of Horse and Ox Shoes; and I do hereby declare the following to be a full, clear, and exact description of the same, reference being had to the accompanying drawings, forming part of this 10 specification, in which—

Figure 1 is a side elevation; Fig. 2, a bottom-plan view, and Fig. 3 an end elevation.

Similar letters of reference in the several figures denote the same parts.

15 The object of this invention is to provide, for the use of farmers and other persons whose business requires the use of horse and ox teams and to whom a blacksmith shop is not readily accessible, a simple and convenient instrument 20 whereby they can themselves at any time, without delay, sharpen the calks of the shoes of their horses or oxen, and thereby save the time, labor, expense, and interruption of their business heretofore necessary in such cases.

25 To this end the invention consists in an instrument constructed as I will now proceed to describe.

In the drawings, A represents an arched frame, constructed in two pieces, *a a'*, jointed 30 together at the point *a²* at the apex of the arch. The movable ends of this frame are connected by a straining-rod, B, which passes through holes in the frame, and is secured by a head, *b*, on one end and a screw-nut, *b'*, on the other, 35 substantially as shown. Below the straining-rod two triangular openings or recesses, *m m'*, are made in each end of the frame, and two files, *c c'*, preferably triangular in cross-section, are secured and held by inserting their extremitiess therein.

The two files lie parallel to each other, preferably with a narrow space between their proximate corners for the escape of the metal filings, and being triangular or of such other prismatic form that different working-faces 45 can be presented by turning or reversing them, they can be at any time adjusted so as to present fresh unworn faces for the performance of the work.

Ordinary triangular files, such as are in common use and well known in the market, can be applied and used in connection with this instrument without the necessity of any special construction therefor.

The mode of inserting, removing, and adjusting the files will be understood from the drawings without further description.

In the use of the instrument the proximate faces of the files *c c'* are brought to bear against the sides of the calk and the instrument moved 60 rapidly back and forth by the operator. As the files act simultaneously upon both sides of the calk, the point or edge of the latter is very quickly brought to the requisite degree of sharpness.

Having thus described my invention, I claim as new—

The calk-sharpener herein described, consisting of the jointed frame A, the two files *c c'*, held in the ends of said frame parallel to each other and with an angular space between them, the straining-rod B, and screw-nut *b'*, substantially as described.

JOSEPH BORLAND.
